CLAIM

I claim the ornamental design for a controller for a surveillance camera, as shown and described.

DESCRIPTION

FIG. 1 is a front, right, and top perspective view of a controller for a surveillance camera showing the new design; FIG. 2 is a rear, left, and top perspective view thereof; FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

The broken lines in the drawings illustrate subject matter that forms no part of the claimed design.
